UNITED STATES PATENT OFFICE.

HAROLD W. SHONNARD, OF MONTCLAIR, NEW JERSEY, ASSIGNOR TO ELEVATOR SUPPLIES COMPANY, INC., A CORPORATION OF NEW JERSEY.

DOOR OPENING AND CLOSING MEANS.

Application filed October 9, 1925. Serial No. 61,623.

The present invention relates to certain improvements in the opening and closing mechanism of sliding doors, and more particularly to such as are used to close the doors 5 ways at the different floors along an elevator shaft.

The principal object of the invention is the provision of means adapted to be quickly mounted during the process of installation, 10 and of such a nature as to be capable of being installed by any ordinary mechanic, instead of requiring the services of specially trained and relatively expensive labor.

Where sliding doors for elevator landings 15 have been used it has hitherto been the practice to supply the various elements of each installation separated, and to rely upon specially trained and high priced operatives to assemble and mount them correctly. The 20 supporting guide rail, the door hangers that run upon said rail, the automatic door closer, the toggle levers and the plates and bolts by which these are fastened and connected have hitherto been assembled at each elevator 25 landing. The mode of operation of the toggle levers in opening and closing the sliding doors is such that every part must be very carefully and accurately placed in order to obtain satisfactory operation. Small errors 30 in adjustment result in material derangement in operation. For instance—the doors do not fully open or close or the toggle levers do not assume correct straight locking position when the doors are closed. Errors of 35 this kind have to be corrected, sometimes with great difficulty, resulting in much loss of time and consequent added expense.

The present invention obviates these difficulties by supplying a complete elevator door 40 equipment, the principal parts of which are assembled once for all in the factory, and serve by their very construction as a perfect guide to easy and correct installation. Incidentally an important feature of the invention 45 is found in the fact that the guide rail and vertical side plate—which are permanently connected in the factory—are mounted directly upon the side wall of the hatch; the elevator door closer being mounted upon 50 said vertical side plate and serving itself as a support for the toggle levers. This is an important improvement over the old plan of

making the toggle levers support the door closer, since lighter material can be used for the toggle levers, and easier operation of the 55 doors is secured.

The invention also includes certain improvements in the details of construction of the door closer, its combination with the usual electric "interlock" and certain improvements of importance where the sliding doors are arranged to be swung at right angles to the hatch wall, to leave the entire door opening clear, as in freight elevator practice.

The invention is illustrated in a preferred 60 form in the accompanying drawings, wherein in Figure 1 is a general view of the preferred construction in elevation with the two sliding doors closed, Figure 2 is a similar view of a part of the same with the doors opened 65 and swung outward to clear the entire doorway, Figure 3 is a view in elevation of the detachable joint for the toggle operating arm, Figure 4 is a plan view of the same, 70 Figure 5 is an exterior view in elevation of the combined door closer and check showing 75 the preferred mode of attaching the toggle arm thereto, Figure 6 is a face view of the same with the toggle arm and front cover plate removed, Figure 7 is a medial vertical 80 section of the same, Figure 8 is a view in front elevation of a modified form, Figure 9 is a partial view in elevation of said modified form with the sliding door opened, Figure 10 is a similar view of a detail on a larger 85 scale, and Figure 11 is a sectional view of detail on the line a—a of Figure 10.

Referring to Figure 1, two doors are shown at 10 and 11, the door 10 being suspended by sheaves 12 which roll along the guide rail 90 13, so that the door 10 may be made to move past the door 11 parallel thereto, as usual in many elevators. This movement is accomplished in a well known manner by the toggle levers 14 and 15, pivotally joined at 16. 95 The lever 14 is pivotally mounted on the door 10 at 17, being operated by the depending lever 18. The second toggle is connected at 19 with the operating shaft of a door closer 20, operated by a spring, by air pressure, or by both. When the door is closed the two toggle levers lie in a common line and serve as an effective lock for the door.

A feature of capital importance in my in-

vention is found in the mode of assembling and mounting, as already stated. In order to secure the advantages above set forth, the guide rail 13 is attached to a side plate 21, at 5 the lower end of which is mounted the automatic door check 20, as shown in Figure 1. The plate 21 is fixed at right angles to the guide rail 13. The guide rail and side plate 21 are fixed directly against the side wall of 10 the elevator shaft, respectively over and beside the door opening, as shown.

It is now only necessary to know the width of the door opening; knowing which, the right length of guide rail 13 is selected, and 15 shipped, drilled ready to be bolted to the side plate 21 bearing the door closer 20, which plate is also ready drilled for bolting. The toggle bars etc. are shipped detached.

The man who installs this apparatus has 20 only to bolt the plate 21 to the rail 13 and bolt the guide rail over the doorway at the proper height for the doors, taking care that this rail is level, which will bring the plate 21 into proper vertical position. He is also 25 furnished with directions as to the horizontal distance of the inner edge of the plate 21 from the edge of the doorway. Having fixed the rail and side plate according to this simple rule, the plate 22 carrying the pivot 17 is fixed 30 at the middle of the door 10 level with the shaft 19 of the door closer. The toggle bars are then mounted in level position with the door 10 closed and properly joined at 16 according to the lengths required. This 35 completes the mounting of the essential parts, it being understood, of course, that the necessary adjustment of the closing spring tension is accomplished.

A removable guard bar 23 is supplied on 40 the door 10 to guide and confine the swinging lever 18.

The features hitherto described may be used in combination with automatic door closers of any suitable type without departing from the broad invention. My invention 45 in its narrower aspect, however, comprises an improved form of spring-operated door closer which I shall now describe.

As shown clearly in Figure 7, the end of 50 the toggle bar 15 is fixed to the operating shaft 19 of the door closer, which shaft is provided with a toothed wheel 24 cooperating with a pawl 25, Fig. 5, to maintain the desired tension on the spiral closing spring, the ends 55 of which are shown at 26 and 27 in Figure 6. When in horizontal locked position, the toggle arm 15 comes down against an adjustable screw stop 28, turning in a threaded socket 29, Fig. 5. The particular form of 60 door closer shown is adapted for use on either side of the door, and thus the pin 28 may be screwed into either socket 29 or 30, as circumstances require.

The provision of an automatic door closer 65 and check having a construction suited to the

novel mounting above described was found to involve problems and practical difficulties which are disposed of by my invention in the manner shown in detail in Figures 5, 6 and 7.

The general casing 31 for the closing spring, door check and "interlock switch," has an opening in front through which projects the stationary spindle 32, upon the outer squared portion of which is fitted the ratchet 70 75 24 already described. This spindle forms a bearing for the hollow operating shaft 19 of the door closer, upon a squared portion of which is fitted the end of the toggle arm 15.

In order to serve as an adjustable point of fixture for the operating spring 26, the spindle 32 has a centrally bored cavity at its inner end which finds a bearing on the cylindrical stub 33 carried by the removable back plate 80 85 34.

The inner end of the operating shaft 19 carries a cylindrical barrel 35 to which is attached the outer end of the door-closing spring 26. This barrel 35 is furnished with teeth 36 which mesh with the rack 37 on the top of the plunger 38, forming a part of the door check. This plunger moves in an oil chamber at the opposite ends of which are vents controlled by the needle valves 39 and 40. As the plunger is pushed through the oil chamber by the teeth 36 on the barrel 35, its movement is retarded by the resistance of the oil to passage through the vents and through the connecting pipe 41. The degree of retardation can be varied by suitable adjustment of the needle valves. Since the barrel 35 can only move with the toggle arm 15, it follows that the retardation effected by the plunger 38 acts through the barrel and toggle arms to check the door movement.

As clearly shown in the drawings, this door check is effective with either right hand or left hand closing doors, and prevents slamming either when opening or closing the door.

While not essential to the invention in this connection, I prefer to combine with the structure just described a suitably combined electric switch to prevent operation of the elevator save when the door is closed and locked by the toggle arms. For this purpose there is mounted upon an enlarged portion of the shaft 19, just within the casing 31, a toothed gear 42. The central opening of this gear is square and fits over flattened portions of the shaft 19, so that the shaft and gear have to move together. As this gear turns with the shaft 19 and toggle arm 15, its teeth cooperate with those on the toothed sector 43 to turn the revoluble member of an electric switch one way or the other.

This switch comprises fixed conducting springs 44, 45, for closing circuit through the movable member of the switch, to effect the electrical interlocking as above mentioned.

This interlock switch is in itself old and well known and is not herein shown or described. The movable member of the switch comprises a revoluble stub shaft 46 fixed to and turning with the toothed sector 43, upon which is immovably mounted a non-conducting body 47 having curved shoulders and intermediate, flat portions, as shown. Upon the curved shoulders are mounted contact plates 48, mutually connected electrically, so that, when the springs 44, 45, lie against these plates the interlock circuit is closed. On the other hand, when the switch is turned by opening the door so that the springs 44, 45 lie against the pointed portions of the body 47, circuit is open and the elevator cannot be moved. This form of switch is shown and claimed in U. S. Patent No. 1,541,015. It is not herein claimed, save as combined substantially as described with the door closing means.

An important feature of this invention is found in the means whereby, when desired, the toggle arms may be disconnected from the doors, folded and supported temporarily in a substantially vertical position upon the door check 20, or other permanent pivotal support on the vertical plate 21. This is often found desirable in order to swing the doors out of the door opening, so as to make the entire width of this opening available for the passage of freight etc. It is a conspicuous advantage of this improvement that this removal of the toggle arms from the doors may be accomplished without removing a single bolt, nut or other fastening.

The means for accomplishing the ends last named are illustrated in Figures 1, 2, 3 and 4. As shown in Figures 3 and 4, the pin 17 on the plate 22, which affords the pivotal connection between the door 10 and the toggle arm 14, passes through a slot 49 in the arm 14, at the end of which is a circular enlargement 50 of sufficient diameter to permit passage of the head 51 on the pin 17.

The operating lever 18, by means of which the elevator attendant moves the toggle arms in opening the door, is shaped with a bend at the end (see Fig. 3) which is normally held flat against the end of the arm 14 by a nut 52 on the threaded pin 53, which passes through the lever 18. This pin is preferably mushroomed at its outer end to prevent complete removal, and possible mislaying of the nut. The extremity of the lever 18 is so shaped as to partly embrace or fit partly around one side of the head 51 on the pin 17, when in the working position shown in Figure 3. When so placed it confines the pin 17 to the narrow portion of the slot in the arm 14.

When the parts are in operative position, the lower end of the operating lever 18 can be swung behind a guide strip 23 which can be unfastened at one end and sprung outward

far enough to allow the lever 18 to be swung from under it.

When it is desired to remove the toggle levers from the doors, preparatory to swinging them out of the doorway, the nut 52 is loosened sufficiently to permit the end of the lever 18 to be drawn forward out of the plane of the head 51 on the pin 17. The door 10 can then be moved far enough to bring the head 51 opposite the enlargement 50 in the slot 49. The toggle arm is then sprung forward, which frees it at once from engagement with the door 10; and, by similarly springing the arm 15 off the pin 16 on the door 11, both doors are left free. The toggle arms and operating lever can then be folded together so as to be supported upright over the shaft of the door check 20 by engaging the pawl A with the lug B on the lever 15 as shown in Figure 2.

The door 11 is hinged in the usual manner, to permit it to swing away from the beholder in Figure 2. The door 10 is swung on pins 54 and 55; the former affording a pivotal connection with the strip 56 supported by the sheave 12, and the latter sliding along a slot in the bottom rail or sill of the door. Upon releasing the door 10 at the bolt 57, it can be swung outward on the pins 54, 55, as shown in Figure 2, thus leaving the entire door space open.

In Figures 8, 9, 10, and 11 there is shown a modified form of this invention in which the depending lever 18 is replaced by a simple straight extension 58 of the toggle arm 14.

Normally this toggle arm with its extension 58 is pivotally connected with the sliding door 10 by means of a pin 59 which is fixed upon a plate 60 preferably extending across the door 10. The pin passes through a circular opening in the center of a hub 61 carrying a pivoted locking latch 62. When all the parts are in their normal working position as shown, the latch 62 engages an annular notch 63 in the pin 59, and so prevents withdrawal of the toggle arm 14. In this position the latch is preferably secured by the well known friction lock of the ball and spring type shown at 64.

When the toggle arms are to be disconnected; in order to swing the sliding door at right angles to normal position, it is only necessary to swing the latch 62 out of the notch 63 (see dotted lines in Figure 10) and then draw the hub 61 off of the pin 59.

In Figures 9 and 10 there is shown a simple form of lock adapted for use with this form of the invention in case the operator of an elevator wishes to leave the cage with the door open. This lock comprises a swinging catch 65, turning on the pin 66 and adapted to be swung into position to engage a shoulder 67 in the hub 61, as clearly shown in Figure 10.

The details of door operating structure and the combination thereof with the inter-

lock switch are not herein claimed, as they form the subject matter of a divisional application for patent filed January 28, 1928, Serial No. 250,168.

5 My improved construction may be modified in many ways without departing from the scope of my invention, which is not limited to the details herein shown and described.

10 What I claim is—

1. In a door operating device, a unitary support adapted for attachment against a wall comprising a horizontal guide rail, a side plate fixed at right angles thereto near one end thereof and means near the lower end of said side plate adapted to afford a pivotal support to a toggle bar.

2. Apparatus as in claim 1, wherein the pivotal support for the toggle bar comprises an automatic door closing device. 20

3. In apparatus for operating a sliding door, toggle arms detachably pivoted to said door, the pivot of one of said arms having a notch, and a swinging locking latch on the other arm adapted to engage in said notch. 25

4. In apparatus for operating a sliding door, toggle arms detachably pivoted to said door, in combination with a locking latch pivotally mounted on the door and adapted to engage a shoulder on one toggle arm. 30

In testimony whereof I hereto affix my signature on this 7th day of October, 1925.

HAROLD W. SHONNARD.
